FLORAL ARRANGER

James B. Swett, Barrington, R.I., assignor to Rexall Drug and Chemical Company, Los Angeles, Calif., a corporation of Delaware

Filed Oct. 23, 1962, Ser. No. 72,236

Term of patent 14 years

(Cl. D35—3)

FIG. 1

FIG. 2

I claim:

The ornamental design for a floral arranger, as shown.
